United States Patent Office

Des. 211,370
Patented June 11, 1968

211,370

TIE RACK

James Paul Morrison, 2311 W. Azalea St.,
Tyler, Tex. 75701

Filed June 20, 1967, Ser. No. 7,525

Term of patent 7 years

(Cl. D33—8)

I claim:

The ornamental design for a tie rack, substantially as shown.
